Primary Examiner — Vy N Koenig*Assistant Examiner* — Omeed Agilee(74) Attorney, Agent, or Firm — Thorpe North & Western, LLP; David W. Osborne(57) CLAIM

The ornamental design for a bottle, as shown and described.

DESCRIPTION

FIG. 1 is a perspective view of a bottle in accordance with my invention;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines in the drawings are included to show portions of the bottle that form no part of the claimed design.
